UNITED STATES PATENT OFFICE

2,583,433

WATER-COOLED SHAKER GRATE DIVIDER

Raymond M. Losch, Summit Station, Pa.

Application June 1, 1950, Serial No. 165,385

1 Claim. (Cl. 122—371)

1

This invention relates to coal, refuse, and other fuel burning grates of the shaker type and also of the type wherein the bed of the grate is formed of a flat substantially hollow casing with comparatively small air tubes extended therethrough, and in particular this invention relates to a substantially hollow perforated grate having a water filled beam providing a divider extended across the grate and spaced from one end thereof.

The purpose of this invention is to provide a water cooled shaker grate wherein means is provided for confining the fire to a comparatively small section thereof whereby only a portion of the grate is available for summer use.

This invention is an improvement over the grate of the prior patents of Cyrenius Losch numbers 1,840,117 and 1,939,177, in that a substantially hollow water cooled beam is provided on the surface of the grate for dividing the grate into sections.

It is difficult to regulate the fire in domestic and commercial coal burning furnaces whereby sufficient heat is obtained for the residence or building during the winter and only sufficient heat for hot water is provided during the summer. For this reason auxiliary hot water heaters are used whereas it would be less expensive to maintain a small fire in the main heating plant. With this thought in mind this invention contemplates means for dividing the grate of a furnace whereby a plurality of different sizes of fires may be maintained on the grate so that the device provides means for maintaining a large fire over the entire area of the grate, a small fire at one end of the grate, or an intermediate fire over the opposite end of the grate.

Another object of the invention is to provide means for dividing water cooled shaker grates to provide a small and a large fire wherein the dividing element may be applied to grates now in use.

A further object of the invention is to provide an improved water cooled shaker grate having a divider in combination therewith which is of a simple and economical construction.

With these and other objects and advantages in view the invention embodies a substantially hollow grate having upper and lower plates connected at the edges by hollow beams and throughout the intermediate portion thereof by tubular elements which provide air passage through the grate, and a box-like channel shaped or tubular beam extended from the front to the rear of the grate, spaced from one end thereof and having openings in the lower side communicating with the area between the plates of the grate.

Other features and advantages of the invention will appear from the following description taken in connection with the drawings wherein:

Figure 1 is a sectional plan through the im-

2

proved water cooled shaker grate showing a coal feeding channel with openings therein through which coal passes to the surface of the grate and with a cover over some of the openings and also a cover over an unused section of the grate.

Figure 2 is a cross section through the water cooled shaker grate shown in Figure 1 taken on line 2—2 thereof.

Figure 3 is a cross section through the grate taken on line 3—3 of Figure 1 illustrating the positions of air ducts under the grate.

Figure 4 is a detail illustrating the hollow water cooled beam providing the divider.

Referring now to the drawings wherein like reference characters denote corresponding parts the improved water cooled shaker grate of this invention includes a hollow beam 10, a grate having an upper plate 11, a lower plate 12, hollow end beams 13 and 14, and tubular sections extended through and connecting the plates 11 and 12 as indicated by the numeral 15.

The dividing beam 10 is channel shaped in cross section having a back 16 with side flanges 17 and 18, and a plate 19 is positioned across the outer end providing a closure, therefor. The inner end 20 of the divider is welded to a hollow beam 21 extended across the front of the grate, as shown in Figures 1 and 3. The edges of the back 16 and side flanges 17 and 18 are welded to the face 22 of the hollow beam 21. The upper plate 11 of the grate is provided with a plurality of spaced openings 23 that provide communicating means between the interior of the dividing beam 10 and the grate.

The beam 10 opens into the back header or beam 21 of the grate and the water or other liquid circulates from the interior of the grate through the holes 23 into the divider and through the divider to the back header or hollow beam 21, from where it is circulated to the boiler.

The openings 24 of the tubular elements 15 between the plates 11 and 12 of the grate provide air circulation through the body or bed of the grate and, as illustrated in Figure 3 air under pressure or a forced draft may be supplied to the entire grate or to sections thereof through a duct 25 that communicates by means of openings 9 with an air chamber 26 which is positioned against the lower surface of the grate.

In the design shown coal or other fuel is supplied to the grate through a feeder channel 27 which is provided with spaced openings 28, 29, and 30 whereby coal is supplied to the section or sections of the grate desired. The openings are provided with vertically disposed chutes 31, as shown in Figure 3 and when it is desired to use only the small section of the grate between the divider 10 and end beam 14 the openings 28 and 29 are covered by a plate 32 that may be secured in position by a screw 33. At the same time a

cover plate 34 is placed over the body of the grate to cover the air passages 24 therethrough.

With the parts arranged in this manner the grate, which is suspended on rockers 35 and 36 is actuated by a motor 37 through shaker instrumentalities in a housing 38, an arm 39 and a bracket 40. The grate is resiliently held by springs 41 and 42 on bolts 43 and 44, respectively.

A fan 45 is provided on the motor shaft for supplying air under pressure to the duct 25.

With the parts arranged in this manner the divided shaker grate may be installed in a furnace of any suitable type and for ordinary use the entire surface of the grate is used as a burning area whereas during the summer when only a comparatively small fire is desired fuel is supplied only to the section of the grate between the divider 10 and end beam of the grate. By this means the remainder of the grate is water cooled and therefore is not damaged.

With the fire confined to a comparatively small area of the grate only a small amount of fuel is used as compared with the amount of fuel required to maintain a small fire over the entire grate area.

It will be understood that modifications may be made in the design and arrangement of the parts without departing from the spirit of the invention.

What is claimed is:

In a water cooled shaker grate, the combination which comprises a substantially hollow grate having spaced upper and lower plates connected at their edges with spaced tubular air circulation elements connecting the plates and distributed over the intermediate area thereof, means to con-

duct air to the lower ends of the air circulation elements, a hollow beam position on the top of said grate and extending from the front toward the rear of said grate and spaced from one end thereof, the said upper plate of the grate having circulating openings therein connecting the interior of the beam with the space within the grate surrounding said spaced air circulating elements, a horizontally disposed fuel feeding channel having openings therethrough for the passage of fuel to sections of the grate, means for excluding the fuel from one of the sections comprising a plate for covering some of said openings, a cover plate extended over a section of the grate to close the said tubular air carrying elements of the grate from which the fuel is excluded, and means supplying a cooling fluid to said space within the grate, and an outlet means for the egress of cooling fluid from said beam after cooling fluid has passed through the beam.
